[57] CLAIM

The ornamental design for freezer cabinet, as shown and described.

DESCRIPTION

FIG. 1 is a perspective view of a freezer cabinet, showing my new design;

FIG. 2 is a front elevational view thereof;

FIG. 3 is a top plan view thereof;

FIG. 4 is a right side elevational view thereof, the other side being identical;

FIG. 5 is a bottom plan view thereof;

FIG. 6 is a rear elevational view thereof;

FIG. 7 is a perspective view of the second embodiment of the design shown in FIG. 1;

FIG. 8 is a front elevational view of FIG. 7;

FIG. 9 is a top plan view of FIG. 7;

FIG. 10 is a right side elevational view of FIG. 7, the other side being identical;

FIG. 11 is a rear plan view of FIG. 7; and,

FIG. 12 is a bottom elevational view of FIG. 7.
